Patented Oct. 9, 1917.

UNITED STATES PATENT OFFICE.

THOMAS F. NASH, OF BAILEYVILLE, ILLINOIS.

SERVING-STAND.

1,242,225.

Specification of Letters Patent.

Patented Oct. 9, 1917.

Application filed February 5, 1917. Serial No. 146,802.

To all whom it may concern:

Be it known that I, THOMAS F. NASH, a citizen of the United States, residing at Baileyville, in the county of Stephenson and State of Illinois, have invented certain new and useful Improvements in Serving-Stands, of which the following is a specification, reference being had to the accompanying drawings.

10 This invention relates to an improved serving stand, and has for its primary object to provide a simply constructed device of this character designed for use as a center piece for dining tables.

15 It is a more particular object of the invention to provide a serving stand including a base, a rotatable support mounted thereon, and means for detachably retaining a glass plate or mirror upon the support upon 20 which the dishes or other receptacles are arranged.

25 It is a further general object of my invention to provide a device of the above character which is neat and attractive in its appearance, may be easily cleaned, and is highly serviceable and convenient in practical use.

With the above and other objects in view, my invention consists in the novel features 30 of construction, combination, and arrangement of parts to be hereinafter more fully described, claimed and illustrated in the accompanying drawing, in which,

Figure 1 is a side elevation illustrating 35 the preferred embodiment of my invention;

Fig. 2 is a section taken on the line 2—2 of Fig. 1; and

Fig. 3 is a top plan view of the support, the removable glass disk or mirror being 40 partly broken away.

Referring in detail to the drawing, 5 designates the base of the serving stand which, in the illustrated embodiment of the invention, is of star-shaped form, the arms of 45 said base being preferably skeletonized as shown, for the sake of economy and lightness. The tips or terminals of these base arms have rubber disks or lugs 6 fixed to their bottom faces to rest upon the table and 50 prevent marring of the polished surface. The central portion of the base 5 is likewise of skeletonized construction and includes the central, circular disk 7 connected by the radially disposed arm 8 to the body portion 55 of the base. The central disk 7 and the con-

centric edge of the base plate are provided with suitable raceways to receive the two series of bearing balls indicated at 9.

10 designates the base portion of the rotatable pedestal or support which includes 60 the central disk 11, an outer annular portion 12, and the radial arms 13 connecting said disk and annulus. This pedestal base is loosely mounted for rotation upon the base 5 of the stand by means of a bolt 14 65 centrally disposed through the disks 7 and 11. It will be understood that the under side of the disk 11 and the annulus 12 are also each provided with a raceway to receive the respective series of bearing balls 9. 70

Upon the pedestal base, at the juncture of the radial arms 13 with the outer annular portion 12, vertically disposed posts or standards 15, preferably of nickelized steel, are suitably secured at their lower ends. 75 Upon the upper ends of these standards, a circular plate or disk 16 is rigidly fixed. This disk 16 is provided upon its perimeter, at equidistantly spaced points, with the spring catches or holding devices 17. Upon 80 the upper surface of the disk 16, a circular plate or disk of glass 18 is adapted to be arranged. This disk may be either transparent or in the form of a mirror. The spring catches 17 are adapted to snap over the outer 85 edge of the glass disk 18, as will be readily understood, and detachably hold the same in place upon the top plate 16 of the pedestal.

From the foregoing description, the construction and manner of operation of the device will be readily understood. The eatables contained in dishes or other suitable receptacles, are disposed upon the mirror or glass disk 18, and the pedestal may be 90 readily rotated upon the base 5 by means of the series of spring catches 17 so as to position any desired dish where it may be easily accessible to one of the diners. All of the metal parts are preferably nickelized 100 and highly polished so that they can be readily cleaned, and the glass disk or mirror 18 can be easily removed from the plate 16 and also thoroughly washed and cleaned. The entire device is about two inches in 105 height and may be readily lifted and removed from the table when desired. The invention may be embodied in various other ornamental forms than that illustrated, and can also be constructed in a variety of sizes. 110

The several elements employed can likewise be modified in many respects and it will, therefore, be understood that I reserve the privilege of adopting all such legitimate changes as may be fairly embodied within the spirit and scope of the invention as claimed.

Having thus fully described my invention, what I desire to claim and secure by Letters

10 Patent is:

1. A serving stand including a base, a pedestal rotatably mounted on the base consisting of a ring or annulus and a plurality of equidistantly spaced standards fixed thereto, 13 a metal disk secured upon said standards and of greater diameter than the base, a removable glass plate of the same diameter as said disk, and means on the disk to detachably

hold the glass plate upon the upper surface thereof.

2. A serving stand including a base, a pedestal rotatably mounted upon said base and having a plurality of equidistantly spaced, vertical standards, a metal disk fixed upon the upper ends of said standards, a glass supporting plate adapted to be arranged upon said disk, and a plurality of resilient latch elements fixed to the periphery of said disk to co-act with the plate and detachably hold the same upon said disk.

In testimony whereof I hereunto affix my signature in the presence of two witnesses.

THOMAS F. NASH.

Witnesses:

CHARLES POPP,
HENRY NIEHAUS.
